HOIST

William C. Anthony, Streator, Ill., assignor to
 Anthony Company, Streator, Ill., a corporation
 of Illinois

Application April 24, 1940, Serial No. 331,403

20 Claims. (Cl. 254—93)

This invention relates to a hoisting apparatus and in the particular form here shown is embodied in a hoist of the type generally suitable for hoisting or raising automotive vehicles and similar apparatus so that it may be repaired, inspected and otherwise worked upon. The mechanism here shown comprises a plurality of hydraulic elevating or raising means and includes automatic means for synchronizing the several hydraulic raising means to make sure that they rise equally so that whatever is being raised—an automobile or the like—is constantly and automatically held level. An object of the invention is, therefore, to synchronize a plurality of hoisting means so that whatever is being raised is constantly held level. Another object is to synchronize a plurality of hydraulic hoisting means to effect level raising. Another object is to provide an automatic electrical control for synchronizing and maintaining level a plurality of hoisting means whether they be hydraulic or not.

Other objects will appear from time to time throughout the specification and the claims.

The invention is illustrated more or less diagrammatically in the accompanying drawings, wherein:

Figure 1 is a plan view with parts broken away and parts in section, showing a hydraulic hoist assembly suitable for raising automobiles;

Figure 2 is a side elevation of the structure shown in Figure 1 with parts omitted in raised position;

Figure 3 is an end view on an enlarged scale of the device shown in Figures 1 and 2, with parts omitted, in lowered position;

Figure 4 is a vertical sectional detail with parts in elevation, taken on an enlarged scale at line 4—4 of Figure 1;

Figure 5 is a longitudinal sectional detail on an enlarged scale, showing the hydraulic valve of Figure 1;

Figure 6 is a schematic wiring diagram showing the electrical connections for the control of the mechanism shown in the other figures;

Figure 7 is a schematic detail illustrating the electrical control for the valves and other parts shown in Figure 3.

Like parts are designated by like characters throughout the specification and the drawings.

The mechanism of the present invention may be mounted on any support. It need not be fixed to that support. It may, however, be secured to a prepared base such as a floor. As shown, a floor or foundation or supporting surface 1 carries the mechanism and upon it are four fixed pistons 2a,

2b, 2c and 2d. Each of the pistons is preferably attached to a base plate 3 which actually contacts the supporting surface upon which the apparatus rests. At their upper ends the pistons 2 may carry piston members 4 which are provided, if desired, with suitable contacting or packing surface members.

Positioned about each of the pistons 2, 4 is a cylinder 5. Since the assembly as shown is intended primarily for raising an automobile, the 10 pistons and cylinders are arranged in a rectangle which is longer than it is wide. The two cylinders at each end are, therefore, preferably joined by cradle members 6 which may be depressed or notched as at 7, 7 to permit passage of the wheels 15 of the vehicle, and the cradle members 6 may be additionally fastened to the cylinders by webs 8, 8, and they are joined together by longitudinal frame members 9, 9. In the form here shown, these frame members are I beams. These beams 20 serve to tie the mechanism together and, under many conditions, to support the load which is to be raised, and they serve also to support the controlling and hoisting mechanism.

Upon one of the cylinders 5, there is mounted 25 a supporting platform or frame 10. This frame carries a large part of the mechanism including the pump, the sump and many of the control devices so that the entire hydraulic drive and its control rises and falls when the apparatus is 30 in use. Upon the frame is mounted a sump 11 and upon the sump is mounted a housing 12 within which the electrical control devices are housed. A handle 13 extends outwardly for operation of this control device or switch assembly and means 35 are provided for an electrical connection 14 which may be plugged into a plug 15 to connect the system with a source of current. Beneath the frame 10 is mounted the driving motor 16. This motor is connected to a pump 17 by a connection 18 so that the pump is driven by the motor when energized.

Each of the cylinders 5 is connected by suitable piping with the pump so that each is supplied with pressure fluid. Thus, a pipe 19 runs from 45 the pump 17. A check valve 20 may be positioned in the line and a pressure relief valve 21 may also be positioned in the line. The pipe 19 is continued beyond the pressure relief valve 21. It may be provided with a shield 22 which is positioned over it and prevents its being broken when the wheel of a vehicle passes over it. The lower edges of the shield 22, as shown in Figure 2, are on the same level as the bottom of the members 9. Like them, the shield rests upon the ground or 50 55

floor, when the hoist is in the lowered position. The pipe 19 may be carried through or under the member 7 and one of the members 9. In that case no shield would be necessary. The pipe 19 is connected to a pipe 23 supported upon one of the frame members 9. This pipe extends to both ends of the frame assembly. At the righthand end of the frame, as shown in Figures 1 and 2, it extends partly across the cradle member 6 and there communicates with a pipe 24 which at one end as at 25 connects with one cylinder 5 and at the other end as at 26 connects with the other cylinder 5. Solenoid valves 27, 28 are inserted, respectively, in the pipe sections 25, 26, and are operated to control the passage of fluid to and from their respective cylinders. They are provided, respectively, with solenoids 29 and 30 which are operated in a manner which will be described below. The righthand cradle member 6 shown in Figures 1, 2 and 3 is provided also with a pair of mercury switches 31 and 32. Adjacent its righthand end, as shown in Figures 1 and 2, the pipe 23 is provided with a solenoid valve 33 which is operated by a solenoid 34.

At the lefthand end, as shown in Figures 1 and 2, the arrangement of pipes, valves and solenoid is substantially the same as that described above for the righthand end. There is, thus, a pipe 35 which is joined to the pipe 23 and which, by means of sections 36 and 37, communicates pressure fluid to the two cylinders 5, 5 at that end of the apparatus. Each of the sections 36 and 37 is, respectively, controlled by solenoid valves 38, 39, which are, respectively, operated by solenoids 40, 41. There is also a solenoid valve 42 adjacent the lefthand end of the pipe 23 which is operated by a solenoid 43. There is also positioned on the lefthand cradle 6 of Figures 1 and 2 a pair of mercury switches 44 and 45.

Positioned upon one of the I beams 9 is a pair of mercury switches 46 and 47. In each case the respective pairs of mercury switches mentioned are positioned adjacent the center line of the member which supports them; one being positioned slightly to the left of the center line and the other being positioned slightly to the right of that line.

The pressure fluid flows from the sump 11 to the pump 17 through a pipe or passage 48 and fluid may be returned to the sump by a pipe or passage 49 which is connected to the pressure relief or "pop-off" valve 21 so that fluid escaping through this "pop-off" valve when the latter is operated will be returned to the sump through the pipe 49.

A bleeder pipe 50, 51 is provided in the system and is connected at one end to the pipe 19, preferably beyond the check valve and the "pop-off" valve. The pipe 51 is connected at one end to the sump. A solenoid valve 52 is inserted in the bleeder pipe 50, 51 and is provided with a solenoid 53 to operate it.

The hydraulic valve shown in Figure 5 is typical of the solenoid valves shown throughout the drawings and a description of the showing of Figure 5 will suffice for all of them. For the purposes of the description, it will be assumed that the valve of Figure 5 is the valve 52, operated by the solenoid 53 although, preferably, all of the other solenoid operated hydraulic valves are the same. This includes the valves 27, 28, 33, 38, 39 and 42. The solenoid valve is arranged automatically to be and to remain closed except upon actuation of the solenoid. The inlet passage 54 is connected to the pipe 50. The outlet passage

55 is connected to the pipe 51, and a passage 56 is arranged to join them. A valve member comprising two relatively thickened sections 57 and 58 and two thinner sections 59 and 60 is arranged to reciprocate in suitable guides and in the passage 56; thus, it opens and closes that passage, depending upon its position. At its outer end the sliding valve member is provided with a spring 61 which bears at one end against any suitable portion of the housing 52 and at the other against a plate 62 adjustably held in position by a nut 63. At its opposite end the valve is connected to a link or other suitable member 64 which is arranged within the solenoid 53.

Packings 65 are arranged at each end of the valve and engage the sections 57 and 58 to prevent leakage past them from the housing. Ducts 66 and 67 are provided, respectively, about the valve sections 57 and 58, and liquid which leaks past these sections is received in the ducts and then flows through passages 68 and 69 to a passage 70 from which a tube 71 returns the leakage to the sump 11. In the case of the solenoid valves mounted on the framework, they are connected to a return pipe system indicated generally by the numeral "72," and this return pipe system returns the pressure fluid which may leak from any of the solenoid valves to the sump 11, entering that sump as at 73.

While the electrical mechanism may be connected in a variety of ways, that shown in Figures 6 and 7 is one suitable wiring and control arrangement. In general, the control in the raising operation to accomplish and maintain leveling is the opposite for the lowering control and, hence, two circuits are shown. That shown in Figures 6 and 7 in full lines is the raising control circuit; and that shown in Figures 6 and 7 in dotted lines is the lowering control circuit. The dotted line showing is adopted because it is believed that the showing can be made clearer in that manner than by showing both circuits in full lines.

The member 13 is the controlling lever. The lever as shown in Figure 6 is in the "off" or non-operating position. If moved to the left from the position of Figure 7 toward the point marked "X," it is brought into the raising position. If moved to the right toward the position Y, it is brought into the lowering position.

74, 75 are power lines through which electrical current enters from any suitable source to the panel 76 upon which the lever or handle 13 is mounted. These power lines in the particular form here shown would normally be contained in the cable 14 which is plugged into any suitable socket 15.

The raising circuit will now be described. When the lever 13 is moved to the position X, its contact portion 77, which is provided with the lateral enlargements shown and which are insulated from each other, contacts the buttons 78, 78 and also the buttons or points 79, 79, and thus current is furnished to the wires 80 and 81. The motor 16 is connected to these wires by wires 82, 83. The solenoid 30 of the valve 28 is connected to the wire 81 by a wire 84. From the solenoid 30 a wire 85 leads to the mercury switch 31. A wire 86 leads from that switch and is connected to the main wire 80. A wire 87 connects the mercury switch 32 to the wire 86. A wire 88 leads to the solenoid 29 of the valve 27, and a wire 89 connects that solenoid to the wire 81. A wire 90 connects the wire 81 to the solenoid 34 of the valve 33, and a wire 91 connects the solenoid 34 to the mercury switch 46. A wire 92

connects that switch to the wire 80, and a wire 93 connects the mercury switch 47 to the wire 92. The wire 94 also connects the switch 47 to the solenoid 43 of the valve 42. A wire 95 connects 5 the solenoid 43 to the wire 81. A wire 96 is connected to the wire 81 and at one end of the wire 96 is connected the solenoid 40 of the valve 38. A wire 97 connects the solenoid 40 to the mercury switch 45, and a wire 98 connects that switch to 10 the wire 80. A wire 99 connects the mercury switch 44 to the wire 98. A wire 100 connects the mercury switch 44 to the solenoid 41 of the valve 39. The wire 96 is also connected to that 15 solenoid. The circuit described is the circuit that is energized during the raising operation.

The circuit which is used during the lowering operation will now be described. For lowering, the handle 13 is moved to the position Y and in that position it connects the contacts 101 and 102 20 and also connects the contacts 103 and 104, thus furnishing current to the wires 105 and 106.

Since the motor is not needed in lowering, it is not connected to this circuit. A wire 107 is connected to the solenoid 30 of the valve 28. A 25 wire 108 connects that solenoid to the mercury switch 32. A wire 109 connects the mercury switch to the wire 106. The mercury switch 31 is connected by a wire 110 to the wire 109. A wire 111 leads from the mercury switch 31 to the 30 solenoid 29 of the valve 27. A wire 112 connects that solenoid to the wire 105. A wire 113 connects the solenoid 53 of the valve 52 to the wire 106, and a wire 114 connects the solenoid 53 to the wire 105. A wire 115 connects the solenoid 35 34 of the valve 33 to the wire 105 and the wire 116 leads from the solenoid 34 to the mercury switch 47. A wire 117 connects the switch 47 to the wire 106. A wire 118 connects the switch 46 to the wire 117; and a wire 119 connects the 40 switch 46 to the solenoid 43 of the valve 42. A wire 120 connects the solenoid 43 to the wire 105 and to the solenoid 40 of the valve 38. A wire 121 connects the solenoid 40 to the switch 44; and a wire 122 connects the solenoid 44 to the 45 wire 106. A wire 123 leads from the wire 122 to the switch 45. A wire 124 leads from the switch 45 to the solenoid 41 of the valve 39; and a wire 125 connects the solenoid 41 to the wire 105.

Although there is shown an operative form of 50 the device, it will be understood that many changes in the form, shape and arrangement of parts might be made without departing from the spirit of this invention, and it is wished that the showing be taken as, in a sense, diagrammatic.

In particular, many different forms of hoisting 55 means might be used. A mechanical hoisting means might be synchronized and caused to operate at level by the same general control apparatus shown or level controlling devices of many sorts might be used. The mercury valves are suitable and, for many purposes, desirable but other forms of level responsive, circuit controlling means might be used, and the invention is not limited to the use of such mercury switches.

While it is convenient to have the sump and the 60 pump and associated parts arranged to rise and fall as the mechanism rises and falls, that is not essential and they might be positioned on the floor or some other fixed base and connected to the rising portion of the mechanism by means of flexible conduits, pipes and the like. Also, the several pistons 2a, 2b, 2c and 2d need not settle 65 upon the same base. One might be higher than the other or any two might be higher than any 70 other two. The leveling mechanism is such that

the cylinders need not all be of the same size. If desired, the cylinders at one end may be larger than those at the other or the cylinders of either pair may be of different sizes.

The "leveling" means may be used to cause 5 synchronizing or level operation of any number of hoisting means; two or any larger number can be synchronized by the present invention. For some purposes, the pairs of mercury valves can be combined into a single valve. Thus, a single 10 specially formed tube might be substituted, for example, for the pairs of tubes 31 and 32 and with the requisite contacts such switches would operate satisfactorily. The invention is, therefore, not limited either to a plurality of switches 15 or to any particular design of switch.

The use and operation of this invention are as follows:

With the parts in the down position and the control handle 13 in the neutral position shown 20 in Figure 6, no current is supplied to the motor and the system is "dead" and the parts will remain static in whatever position they have been left. If the carriage is at the bottom, it will remain so. If it is at the top or anywhere above 25 the bottom position, it will remain there when the control handle is at the neutral position because liquid cannot pass through the various solenoid valves unless the solenoids are energized. Hence, they remain closed and the liquid is locked 30 in the several cylinders.

Assuming the parts in the down position and that it is desired to raise the carriage, the control lever is moved toward the position X of Figure 6 and by means of the contacts 77 current 35 is supplied to the wires 80 and 81. This, while the parts are still level, energizes all of the solenoids and thus opens all of the valves. The motor is started, it drives the pump and fluid under pressure is supplied to the pipe 23. It flows 40 to the pipe 24 and to both of the righthand cylinders 5. Fluid under pressure also flows to the pipe 35 and to both of the lefthand cylinders 5. Where the words "righthand" and "lefthand" are used, this language applies to the showing on 45 Figures 1, 2 and 6. So long as the carriage rises in a level position, no further control occurs until it is positively stopped by moving the lever 13 or until it stops in the cylinders 5 to contact the piston portions 4. Should excessive pressure 50 develop in the system, the "pop-off" valve 21 will be opened and fluid under pressure will pass through it and into the sump 11. The "pop-off" valve is preferably arranged with a "chattering" means so that, when it is open and fluid is passing 55 through it, it will make a noise and the operator will hear it and will do whatever is necessary to the system.

Should the carriage rise unevenly, the following 60 cycle of operations will occur:

If the righthand end of Figure 2 rises more rapidly than the lefthand end, the mercury in the switch 46 will flow away from contact with the wires 91 and 92, the solenoid 34 will be de-energized, the valve 33 will close and the supply 65 of fluid under pressure to the righthand cylinders will be interrupted and will remain interrupted until the lefthand end has been raised sufficiently to re-establish the level. When that occurs, the mercury in the switch 46 will again contact the wires 91 and 92, the solenoid 34 will be re-energized, the valve 33 will be opened and fluid under pressure will again flow through the pipe 23 to the pipe 24 for supply to the two right-hand cylinders. 70 75

Should one side of the frame rise more rapidly than the other, the same general cycle will be carried out. Figure 7 illustrates the righthand end of the diagram shown in Figure 6, and a description of the operation of that end will serve for the corresponding operation at both ends. Assuming that the righthand side of the carriage—that is, the side supported by the piston 2b—rises more rapidly than the lefthand side, then the mercury in the switch 32 will flow away from the wires 87 and 88, the solenoid 29 will be de-energized, the valve 27 will be closed and the supply of fluid under pressure through the valve 27 to the piston 2b will be interrupted and that piston will no longer receive fluid under pressure. Fluid will continue under pressure to the piston 2a until leveling has occurred and then the mercury in the switch 32 will flow again to the position of Figure 7, contacting the wires 87 and 88, re-energizing the solenoid 29, re-opening the valve 27 and recommencing the flow of fluid under pressure to the piston 2b.

The general operation described can occur at either end of the system causing a break in the switch 31 or 32 or a break in the switch 44 or 45 and this may occur repeatedly during a raising operation. Similarly, the same operation may occur when one end is raised above the other and will effect breaking of the switches 46 or 47. The provision of two switches at each control point obviously affects the valves for the two sides or the two ends to control them and through them to control the flow of fluid under pressure to the respective pistons or cylinders.

When the machine is raised to the desired point, the lever 13 is moved to the inactive position, the motor is stopped, all of the solenoids are de-energized, all of the valves close and there is a fluid lock which prevents accidental or undesired lowering of the carriage.

When it is desired to lower the carriage, the control handle 13 is moved to the Y position, and by means of the contact 77, current is supplied to the wires 105, 106 and through them to the other wires forming the lowering circuit, which wires are connected to the several mercury switches and to the several solenoids.

The motor is not energized for lowering because gravity is sufficient to force the liquid from the cylinders when the control valves for the cylinders are opened. When current is supplied to the wires 105 and 106, the solenoid valves 27, 28, 33, 42, 38 and 39 are opened and the solenoid valve 52, which was not opened during raising, is now opened. The reason for opening the valve 52 is to permit the fluid, as it is forced out of the cylinders, to return through the pipe 50, 51 into the sump 11. This valve remains open so long as the control handle is in the lowering or Y position.

The same general leveling operation occurs in lowering as that described in raising but there is, in effect, a reversal of this control from right to left. Considering now Figures 2 and 6, should the righthand end lower more rapidly than the lefthand end, the mercury in the switch 47 will flow out of contact with the wires 116 and 118 and will de-energize the solenoid 34, causing the valve 33 to close. Hence, the fluid over the righthand pistons 2a and 2b cannot escape from the pipe 24 into the pipe 23 for return to the sump, and that end of the carriage will stop descending until the lefthand end has caught up to it. When level is restored and the mercury in switch 47 returns to contact with the wires 116 and 118, the

solenoid 34 is re-energized to open the valve 33 to permit escape through it.

The lateral leveling is generally similar to that described above and will be described in connection with Figure 7. Should the carriage descend unevenly so that the righthand side is ahead of the lefthand side, the mercury in switch 31 will flow out of contact with the wires 110 and 111, de-energizing the solenoid 29, closing the valve 27 and stopping the flow of fluid from above piston 2b. Just as soon as level is restored, the mercury in switch 31 returns, contacts the wires 110 and 111, re-energizes the solenoid 29, reopens the valve 27 and permits further return of fluid from above the piston 2b.

The same general cycle of leveling can occur at each end to effect lateral leveling and will occur also to effect longitudinal leveling.

While the means for synchronizing and controlling a plurality of hydraulic hoists has many uses and is not limited to an automobile or vehicle lift, the particular embodiment here shown is directed to that purpose. Among the reasons for providing such "leveling" means are the following: The car or other weight which is to be lifted will very rarely be central with respect to all of the cylinders. The weight will thus be unevenly distributed. The car or other weight will very rarely have its center of gravity at its geometrical center. The surface upon which the lifting means stand may be uneven; in fact, this surface need not be even. The cylinders themselves need not be of the same diameter. Many other reasons why the automatic leveling is desirable will suggest themselves.

I claim:

1. In combination in a hydraulic lift, a plurality of hydraulic lifting assemblies, each including a fixed part and a relatively movable part, and means for supplying fluid under pressure to said hydraulic assemblies, including conduits to each of them, a carriage supported by said movable parts, and means for controlling the movement of said movable parts to maintain the carriage level, said means including a valve for each of said raising assemblies adapted to control the flow of fluid thereto and therefrom through said conduits, an operating means for each of said valves, a plurality of level responsive devices mounted on said carriage, one of said devices for each of said valve operating means, said devices adapted to be operated when said frame moves out of level to cause one of said valves to be closed, to alter the flow of pressure fluid to said raising assemblies until the carriage has been restored to level.

2. In combination in a hydraulic lift, a plurality of hydraulic lifting assemblies, each including a fixed part and a relatively movable part, and means for supplying fluid under pressure to said hydraulic assemblies, including conduits to each of them, a carriage supported by said movable parts, and means for controlling the movement of said movable parts to maintain the carriage level, said means including a valve for each of said raising assemblies adapted to control the flow of fluid thereto and therefrom through said conduits, an electrical operating means for each of said valves, a plurality of level responsive electrical switches mounted on said carriage, one of said switches for each of said valve operating means, said switches adapted to be operated when said carriage moves out of level to cause one of said valves to be closed, to alter the flow of pressure fluid to said raising assemblies until the carriage has been restored to level.

3. In combination in a hydraulic lift, a plurality of hydraulic lifting assemblies, each including a fixed part and a relatively movable part, and means for supplying fluid under pressure to said hydraulic assemblies, including conduits to each of them, a carriage supported by said movable parts, and means for controlling the movement of said movable parts to maintain the carriage level, said means including a valve for each of said raising assemblies adapted to control the flow of fluid thereto and therefrom through said conduits, an operating means for each of said valves, a plurality of level responsive devices mounted on said carriage, one of said devices for each of said valve operating means, said devices adapted to be operated when said frame moves out of level to cause one of said valves to be closed, to alter the flow of pressure fluid to said raising assemblies until the carriage has been restored to level, said carriage comprising a longitudinal element and a plurality of transverse elements, a plurality of said level responsive devices being mounted on each of said elements.
4. In combination in a hydraulic lift, a plurality of hydraulic lifting assemblies, each including a fixed part and a relatively movable part, and means for supplying fluid under pressure to said hydraulic assemblies, including conduits to each of them, a carriage supported by said movable parts, and means for controlling the movement of said movable parts to maintain the carriage level, said means including a valve for each of said raising assemblies adapted to control the flow of fluid thereto and therefrom through said conduits, an electrical operating means for each of said valves, a plurality of level responsive electrical switches mounted on said carriage, one of said switches for each of said valve operating means, said switches adapted to be operated when said frame moves out of level to cause one of said valves to be closed, to alter the flow of pressure fluid to said raising assemblies until the carriage has been restored to level, said carriage comprising a longitudinal element and a plurality of transverse elements, a plurality of said level responsive switches being mounted on each of said elements.
5. In combination in a hydraulic lift, a plurality of hydraulic lifting assemblies, each including a fixed part and a relatively movable part, and means for supplying fluid under pressure to said hydraulic assemblies, including conduits to each of them, a carriage supported by said movable parts, and means for controlling the movement of said movable parts to maintain the carriage level, said means including a valve for each of said raising assemblies adapted to control the flow of fluid thereto and therefrom through said conduits, an operating means for each of said valves, a plurality of level responsive devices mounted on said carriage, one of said devices for each of said valve operating means, said devices adapted to be operated when said frame moves out of level to cause one of said valves to be closed, to alter the flow of pressure fluid to said raising assemblies until the carriage has been restored to level, said carriage including a longitudinal element and a plurality of transverse elements, and having a pair of oppositely directed level responsive devices on said longitudinal element and a pair of oppositely directed level responsive devices on each of said transverse elements, the devices on said transverse elements being operated in response to transverse tilting of the carriage and

the devices on the longitudinal element being operated in response to longitudinal tilting of the frame.

6. In combination in a hydraulic lift, a plurality of hydraulic lifting assemblies, each including a fixed part and a relatively movable part, and means for supplying fluid under pressure to said hydraulic assemblies, including conduits to each of them, a carriage supported by said movable parts, and means for controlling the movement of said movable parts to maintain the carriage level, said means including a valve for each of said raising assemblies adapted to control the flow of fluid thereto and therefrom through said conduits, an electrical operating means for each of said valves, a plurality of level responsive electrical switches mounted on said carriage, one of said switches for each of said valve operating means, said switches adapted to be operated when said frame moves out of level to cause one of said valves to be closed, to alter the flow of pressure fluid to said raising assemblies until the carriage has been restored to level, said carriage including a longitudinal element and a plurality of transverse elements, and having a pair of oppositely directed level responsive switches on said longitudinal element and a pair of oppositely directed level responsive switches on each of said transverse elements, the switches on said transverse elements being operated in response to transverse tilting of the carriage and the switches on the longitudinal element being operated in response to longitudinal tilting of the frame.

7. In combination in a lifting means, four fixed pistons, a cylinder upon each of said pistons, a carriage supported by said cylinders, means for introducing fluid under pressure to said cylinders to cause them to rise with respect to said pistons, and means for maintaining said carriage level, comprising means for controlling the supply of pressure fluid to said cylinders, said controlling means including a plurality of level responsive devices, a plurality of valves, one for each of said cylinders and adapted to control the supply of fluid thereto, a connection from each valve to one of said level responsive devices whereby one of said valves is operated in response to the operation of any of said level responsive devices.

8. In combination in a lifting means, four fixed pistons, a cylinder upon each of said pistons, a carriage supported by said cylinders, means for introducing fluid under pressure to said cylinders to cause them to rise with respect to said pistons, and means for maintaining said carriage level, comprising means for controlling the supply of pressure fluid to said cylinders, said controlling means including a plurality of level responsive devices mounted on said carriage, a plurality of valves, one for each of said cylinders and adapted to control the supply of fluid thereto, a connection from each valve to one of said level responsive devices whereby one of said valves is operated in response to the operation of any of said level responsive devices.

9. In combination in a lifting means, four fixed pistons, a cylinder upon each of said pistons, a carriage supported by said cylinders, means for introducing fluid under pressure to said cylinders to cause them to rise with respect to said pistons, and means for maintaining said carriage level, comprising means for controlling the supply of pressure fluid to said cylinders, said controlling means including a plurality of

level responsive devices, some of them positioned to be affected by lateral tilting of the carriage, a plurality of valves, one for each of said cylinders and adapted to control the supply of fluid thereto, a connection from each valve to one of said level responsive devices whereby one of said valves is operated in response to the operation of any of said level responsive devices.

10. In combination in a lifting means, four fixed pistons, a cylinder upon each of said pistons, a carriage supported by said cylinders, means for introducing fluid under pressure to said cylinders to cause them to rise with respect to said pistons, and means for maintaining said carriage level, comprising means for controlling the supply of pressure fluid to said cylinders, said controlling means including a plurality of level responsive devices, some of them positioned to be affected by longitudinal tilting of the carriage, a plurality of valves, one for each of said cylinders and adapted to control the supply of fluid thereto, a connection from each valve to one of said level responsive devices whereby one of said valves is operated in response to the operation of any of said level responsive devices.

11. In combination in a lifting means, four fixed pistons, a cylinder upon each of said pistons, a carriage supported by said cylinders, means for introducing fluid under pressure to said cylinders to cause them to rise with respect to said pistons, and means for maintaining said carriage level, comprising means for controlling the supply of pressure fluid to said cylinders, said controlling means including a plurality of level responsive devices, some of them positioned to be affected by lateral tilting of the carriage, others positioned to be affected by longitudinal tilting of the carriage, a plurality of valves, one for each of said cylinders and adapted to control the supply of fluid thereto, a connection from each valve to one of said level responsive devices whereby one of said valves is operated in response to the operation of any of said level responsive devices.

12. In combination in a lifting means, four fixed pistons, a cylinder upon each of said pistons, a carriage supported by said cylinders, means for introducing fluid under pressure to said cylinders to cause them to rise with respect to said pistons, and means for maintaining said carriage level, comprising means for controlling the supply of pressure fluid to said cylinders, said controlling means including a plurality of level responsive devices mounted on said carriage, some of them positioned to be affected by lateral tilting of the carriage, others positioned to be affected by longitudinal tilting of the carriage, a plurality of valves, one for each of said cylinders and adapted to control the supply of fluid thereto, a connection from each valve to one of said level responsive devices whereby one of said valves is operated in response to the operation of any of said level responsive devices.

13. In combination in a lifting means, four fixed pistons, a cylinder upon each of said pistons, a carriage supported by said cylinders, means for introducing fluid under pressure to said cylinders to cause them to rise with respect to said pistons, and means for maintaining said carriage level, comprising means for controlling the supply of pressure fluid to said cylinders, said controlling means including a plurality of level responsive electrical switches, some of them positioned to be affected by lateral tilting of the carriage, others positioned to be affected by longitudinal tilting of the carriage, a plurality of valves,

one for each of said cylinders and adapted to control the supply of fluid thereto, a connection from each valve to one of said level responsive switches whereby one of said valves is operated in response to the operation of any of said level responsive switches.

14. In combination in a lifting means, four fixed pistons, a cylinder upon each of said pistons, a carriage supported by said cylinders, means for introducing fluid under pressure to said cylinders to cause them to rise with respect to said pistons, and means for maintaining said carriage level during movement, comprising means for controlling the supply of pressure fluid to said cylinders, said controlling means including a plurality of level responsive electrical switches mounted on said carriage, some of them positioned to be affected by lateral tilting of the carriage, others positioned to be affected by longitudinal tilting of the carriage, a plurality of valves, one for each of said cylinders and adapted to control the supply of fluid thereto, a connection from each valve to one of said level responsive switches whereby one of said valves is operated in response to the operation of any of said level responsive switches.

15. In combination in a lift, a plurality of hydraulic lifting means, each of said means including a fixed member and a movable member, a carriage supported by said movable members, and means for supplying pressure fluid and for controlling the supply of said pressure fluid to said raising means in response to tilting of said carriage, whereby said carriage is retained substantially level, said means including a source of fluid under pressure, conduits supplying said fluid to each of said raising means, a valve for each of said conduits, a plurality of level responsive means upon said carriage, said level responsive means being connected to each of said valves whereby tilting of the carriage in any direction affects one of said valves to cut off supply of fluid to the leading, raising means.

16. In combination in a hydraulic lifting apparatus, a plurality of hydraulic lifting assemblies, each including a fixed part and a relatively movable part, a carriage supported by said movable parts, means for supplying fluid under pressure to said lifting assemblies and for withdrawing fluid from said assemblies, and means for controlling the withdrawal of fluid from said assemblies to maintain the carriage level, said controlling means including a valve for each of the raising assemblies adapted to control the flow of fluid therefrom; an operating means for each of said valves, a plurality of level responsive devices mounted on said carriage, one of said devices for each of said valve operating means, said devices adapted to be operated when said frame moves out of level to cause one of said valves to be closed and thereby to alter the flow of fluid from said raising assemblies until the carriage has been restored to level.

17. In combination in a hydraulic lifting apparatus, a plurality of hydraulic lifting assemblies, each including a fixed part and a relatively movable part, a carriage supported by said movable parts, means for supplying fluid under pressure to said lifting assemblies and for withdrawing fluid from said assemblies, and means for controlling the withdrawal of fluid from said assemblies to maintain the carriage level, said controlling means including a valve for each of the raising assemblies adapted to control the flow of fluid therefrom; an operating means for each of said valves, a plurality of level responsive de-

- 5 vices mounted on said carriage, one of said devices for each of said valve operating means, said devices adapted to be operated when said frame moves out of level to cause the valve controlling the hydraulic lifting assembly which has lowered more rapidly than another to be closed and to stop the flow of fluid from said leading assembly until the carriage has been restored to level.
- 10 18. In combination in a hydraulic lifting apparatus, a plurality of hydraulic lifting assemblies, each including a fixed part and a relatively movable part, a carriage supported by said movable parts, means for supplying fluid under pressure to said lifting assemblies and for withdrawing fluid from said assemblies, and means for controlling the withdrawal of fluid from said assemblies to maintain the carriage level, said controlling means including a valve for each of
- 15 20 the raising assemblies adapted to control the flow of fluid therefrom; an operating means for each of said valves, a plurality of level responsive devices mounted on said carriage, one of said devices for each of said valve operating means,
- 25 25 said devices adapted to be operated when said frame moves out of level to cause the valve controlling the hydraulic lifting assembly which has lowered more rapidly than another to be closed and to stop the flow of fluid from said leading assembly until the carriage has been restored to level, and to reopen the valve when the frame has been restored to level for further discharge of pressure fluid from the assembly from which discharge was temporarily checked.
- 30 35 19. In combination in a hydraulic lift, a plurality of hydraulic lifting assemblies, each including a fixed part and a relatively movable part, and means for supplying fluid under pres-
- sure to said hydraulic assemblies, including conduits to each of them, a carriage supported by said movable parts, and means for controlling the movement of said movable parts to maintain the carriage level, said means including a valve for each of said raising assemblies adapted to control the flow of fluid thereto and therefrom through said conduits, and operating means for each of said valves, a level responsive device mounted on said carriage and provided with operating connections to each of said valve operating means, said device adapted to be operated when said frame moves out of level to cause one of said valves to be closed, to alter the flow of pressure fluid to said raising assemblies until the carriage has been restored to level.
- 10 15 20 25 30 35 20 25 30 35
20. In combination in a hydraulic lift, a plurality of hydraulic lifting assemblies, each including a fixed part and a relatively movable part, and means for supplying fluid under pressure to said hydraulic assemblies, including conduits to each of them, a carriage supported by said movable parts, and means for controlling the movement of said movable parts to maintain the carriage level, said means including a valve for each of said raising assemblies adapted to control the flow of fluid thereto and therefrom through said conduits, an electrical operating means for each of said valves, a level responsive electrical switch mounted on said carriage, said switch having a contact member for each of said valve operating means, and a connection from one of said contact members to the corresponding valve operating means, said switch adapted to be operated when said carriage moves out of level to cause one of said valves to be closed.

WILLIAM C. ANTHONY.
